CORPORATION OF MAINE.

SEWING-MACHINE.

1,197,605.

Specification of Letters Patent. Patented Sept. 12, 1916.

Application filed March 2, 1915. Serial No. 11,532.

To all whom it may concern:

Be it known that we, CHARLES F. CLARK and ALFRED S. CLARK, citizens of the United States, residing at Beverly, county of Essex, State of Massachusetts, have invented an Improvement in Sewing-Machines, of which the following description, in connection with the accompanying drawing, is a specification, like characters on the drawing 10 representing like parts.

This invention relates to sewing machines and has for its object to provide a novel sewing machine in which the stitch-forming instrumentalities are mounted for bodily 15 movement as a unitary structure relative to the work support.

The invention is capable of being embodied in sewing machines of various types and in order to give an understanding of 20 the invention we have herein illustrated it as it might be embodied in a sewing machine of the "blind stitch" type wherein the blind stitches are formed by making a bend in the work and then thrusting the needle 25 through the bent portion of the work. We desire to reiterate, however, that the invention is not limited in its use to blind stitch sewing machines but is capable of application to various other types of sewing ma- 30 chines.

The machine herein illustrated is constructed so that the needle will penetrate the bent portion of the work at alternate thrusts thereof with the result that one stitch will 35 be formed in the work and the next stitch will be formed to overlie the underside of the work. In the present embodiment of our invention we secure this end by moving the stitch-forming instrumentalities as a 40 unitary structure toward and from the groove into which the work is bent and in timed relation with the operation of the needle, the bodily movement of the stitch-forming instrumentalities operating to place 45 the needle during one penetrating thrust thereof in a position to penetrate the work and to place said needle during the next thrust in a position to pass beneath the work, it being understood that the needle 50 thread is interlooped with the shuttle thread at each thrust of the needle.

In the present embodiment of our invention the work is acted on continuously by a bender as it is fed over the groove, and the

bender thus makes a continuous bend in the 55 work. The work, therefore, is stationary except for the feeding movement, and the needle is caused to pass through the work or beneath it by the bodily movements of the 60 stitch-forming instrumentalities.

In the selected embodiment of the invention herein illustrated, Figure 1 shows a sewing machine embodying our invention in plan view with all of the work support removed except that portion containing the 65 bending groove; Fig. 2 is a section on the line 2—2, Fig. 1 and 2—2, Fig. 3; Fig. 3 is a section on the lines 3—3, Figs. 1 and 2; Fig. 4 is an end view of the machine; Fig. 5 is a perspective view of the stitch-forming 70 instrumentalities and the movable carrier in which they are sustained; Fig. 6 is an enlarged section on the line 6—6, Fig. 1.

We have chosen herein to illustrate our invention as embodied in a machine of that 75 type having a work support 1 provided with a bending groove 2 into which the material 3 to be operated on is bent, and stitch-forming instrumentalities comprising a needle 4 operating beneath the work support and a shuttle 5 co-operating with the needle to produce 80 the stitches. Machines of this type are used for various purposes among which may be mentioned the finishing of buttonholes, machines for this latter purpose being known 85 to the trade as buttonhole-finishing machines.

In the present invention the stitch-forming instrumentalities comprising the needle 4 and shuttle 5 and their operating parts are 90 sustained on a frame or carrier which has a movement relative to the bending groove 2 and in timed relation to the operation of the stitch-forming mechanism.

The various parts of the sewing machine 95 are herein shown as supported by a bed frame 6 which may have any suitable construction, but is herein shown as in the form of a box-like casing provided with a cover 7 which with the part containing the bending 100 groove constitutes the work support 1. This cover 7 is shown as pivotally connected to the bed-frame 6 at 91 so that it can be swung back out of the way to give access to the operative parts.

The bending groove 2 is formed in a block or plate 8 which is fixedly secured to the bed-frame 6, it being herein shown as

sustained on posts or supports 9 rising from the bed-frame, although it might be sustained and held in position by any suitable means without departing from the invention. This block 8 having the bending groove 2 formed therein is stationary. The work 3 is bent into the groove by means of a bender 10 which simply rides on the work 3 as the latter is fed through the bending groove and holds the work in bent position shown in Fig. 6. This bender 10 may have any suitable construction. We prefer, however, to construct it in the form of a roll or wheel which is rotatably mounted upon an arm 11 secured to a post 12. This post 12 is slidably sustained in suitable bearings 13 and 14, and said post is acted upon by a spring 15 which yieldingly holds the bender against the work. This spring is shown as encircling the post and as confined between the bearing 13 and a collar 16 on the post. The post 12 also carries an adjustable collar 17 thereon which co-operates with the bearing 14 to limit the extent of downward movement of the bender 10. The bender can be raised out of engagement with the work when the latter is to be introduced into the machine or removed therefrom by means of a rock-shaft 18 journaled in the bed-frame 6 and carrying an arm 19 adapted to engage the lower end of the post. This rock-shaft can be operated in any suitable way. The device herein shown for this purpose is a handle 20 which is secured to the end of the rock-shaft and is accessible to the operator and is provided with a projection 21 adapted to engage in a notch formed in a resilient retainer 22 which operates to hold the shaft 18 in the position it occupies when the bender is raised.

The work 3 is fed through the bender groove 2 by a feed dog 23 co-operating with the bender 10. This dog 23 operates in a slot 24 formed in the bottom of the groove 2 and is carried by a lever 25 pivoted at 26 to an arm 27 carried by an oscillatory rock-shaft 28, the oscillations of the rock-shaft 28 thus serving to give a longitudinal or reciprocatory feeding movement to the dog 23. Said dog is also given a vertical movement to bring it into feeding contact with the work and then withdraw it from the work after the feeding movement. This vertical movement is secured from a rock-shaft 29 suitably journaled in the frame and having fast thereto a bifurcated arm 30 between the parts of which the end of the lever 25 operates. This arm carries a pin 31 operating in a slot 32 formed in the lever 25. The oscillatory movement of the rock-shaft 29 will thus give a vertical movement to the feed dog, and the oscillation of the shaft 28 will give the backward and forward movement thereto.

65 The rock shafts 28 and 29 receive their

motion from a drive shaft 33 which is operated by any suitable means, such as a drive pulley 34. The desired motion is communicated from the drive shaft 33 to the rock-shaft 28 by means of a cam or eccentric 34 70 operating between the forked end of a lever 35 which is carried by a rock shaft 36 journaled in suitable bearings 37. This lever 35 is connected by a link 38 with an arm 39 fast on the rock-shaft 28. The connection between the link 38 and the lever 35 is preferably an adjustable one to provide for giving the rock-shaft 28 a greater or less movement. For this purpose the arm 35 is slotted, as shown best in Fig. 4, and the 80 end of the link 38 is adjustable in said slot.

The rock-shaft 29 is operated from the drive shaft through a cam or eccentric 40 operating in the forked end of an arm 41 which is fast on the shaft 29.

85 The needle 4 is mounted in a needle bar 41 which reciprocates in suitable guideways or bearings 42 which are arranged so that the needle moves in a path transversely to the length of the groove 2, the bottom of 90 the latter being provided with a notch or opening 92 in which the needle operates. As stated above, the needle and its needle bar, together with the shuttle 5 and its operating mechanism, are sustained by a frame 95 or carrier which is constructed to have a movement relative to the work support, and in the present embodiment of our invention this frame or carrier is mounted to move vertically toward and from the work support, and the movement is in such timed relation to the operation of the stitch-forming instrumentalities that on alternate thrusts of the needle the latter will pass through the work, as shown in dotted lines, 100 Fig. 6, and on the other thrusts it will pass beneath the work, as shown in full lines Fig. 6. The movable frame in which the needle bar and shuttle are mounted is shown at 45 and it may have any suitable construction adapted to sustain these parts. The bearings 42 for the needle bar are carried by this frame. This frame or carrier may be mounted for vertical movement toward and from the bending groove in any appropriate way. One convenient construction is that herein illustrated wherein the carrier is mounted on a rock-shaft 46 which is journaled in bearings 47 formed on the bed-frame 6 of the machine so that said carrier 110 may have a vibratory movement about the rock-shaft as its center.

115 The carrier 45 is given its vibratory movement from the main shaft 33 and for this purpose we have shown said carrier as connected by a link 50 with one arm of an elbow lever 48 journaled in bearings 49 secured to the bed-frame of the machine, the other arm of said lever being connected by a link 51 to an arm 52 secured to a rock-shaft 53 carried 120

in a bearing 54, said arm carrying a shoe 55 operating in a switch cross-over cam member 56 carried by the shaft 33. This construction gives a two-to-one movement, that is, the arm 52 will be moved in one direction during one rotation of the shaft 33 and in the other direction during the next rotation of the shaft 33. This results in elevating the carrier 45 during alternate rotations of the shaft 33 and depressing said carrier during the other rotations. This double cross-over switch cam 56 is of familiar construction and operates to give a comparatively quick movement to the arm 52 while the shaft is making a partial rotation and then to hold said arm in fixed position during the remainder of the rotation.

The connection between the link 51 and the arm 52 is adjustable to provide for giving the carrier 45 a greater or less movement. This adjustment is provided for by the T-slot 57 formed in the arm 52 in which operates the clamping bolt 58 that connects the link to the arm.

25 The needle bar is given its reciprocating movement from the main shaft 33 by means which are not affected by the vertical movement of the carrier 45. As herein shown, the needle bar is pivotally connected by a link 60 to an arm 61 fast on a rock-shaft 62, said rock-shaft having another arm 63 thereon which is pivoted to a yoke-shaped follower 64 that embraces a cam or eccentric 65 fast on the shaft 33.

35 The shuttle 5 may be of any suitable construction. We have herein shown a rotary shuttle which is operated from a shaft 66 journaled in the carrier 45. This shuttle is rotated from the shaft 33 by means which are not affected by the vertical movement of the carrier. While any means for driving the shuttle may be employed, we have shown herein for this purpose a shaft section 67 journaled in bearings in the carrier 45 and geared to the shuttle shaft 66 by bevel gearing 68, said shaft section 67 being connected to the main driving shaft 33 by a connection 70 having one or more universal joints 71 therein. This makes a flexible driving connection between the shaft 33 and the shaft 67 which is not affected by the vertical movements of the carrier 45.

From the above it will be seen that the stitch-forming instrumentalities comprising the needle and the shuttle with their operating parts are carried by a frame or carrier which has a bodily movement relative to the work support so that the stitch-forming instrumentalities as a unitary structure move toward and from the work support in timed relation with the operation of the needle and shuttle. This we regard as an important feature of our invention because it provides a machine in which the needle and shuttle are always maintained in the

proper operative positions relative to each other and yet permits the needle to pass into the work 3 on alternate thrusts and below the work on the other thrusts. This construction also has the advantage that as the material is fed through the machine the bend which is formed therein will be a continuous bend as distinguished from the operation of those machines wherein the bender has a vibratory movement that intermittently bends the work.

Another feature of our invention resides in the fact that the bending member 10 acts also as a presser foot to coöperate with the feeding dog 23 to feed the work so that this element 10 is in fact a combined presser-foot and bender. As stated above, it is not necessary that this combined presser-foot and bender be in the form of a roll, as any shape or construction which would accomplish the desired result may be employed. We prefer the roll form, however, because its rolling contact with the work facilitates the feeding movement.

We have shown at 77 a needle support 90 which comes into position to sustain the needle as the latter is making its penetrating thrust. This needle support is shown as carried by a holder 78 that is slidably mounted in a guideway in the carrier 45 95 and is acted upon by a cam 79 fast on the shaft 67. This cam is so timed that the needle support is raised into operative position as shown in Fig. 5 as the needle approaches the work so that the needle will be 100 supported thereby as it enters the work, said needle support dropping away from the needle in time to prevent the thread passing through the eye of the needle from being cut by its engagement with the support. 105

80 designates a thread tension device of ordinary construction and 81 is a take-up lever through which the thread *t* passes from the tension device to the needle bar. This take-up lever is pivoted at 82 and is 110 actuated by means of a cam 83 on the main shaft.

While in order to give an understanding of our invention, it has been necessary to illustrate and describe one embodiment 115 thereof, yet we wish to state that the invention is not limited to the construction herein shown as this principle of arranging the stitch-forming instrumentalities so that they will have a bodily movement as a unitary structure relative to the work-support, may be applied to sewing machines of other types than that illustrated, and as we believe we are the first to embody this principle in a sewing machine, we desire to claim 120 it broadly.

We claim:

1. In a sewing machine, the combination with a work support having a work-bending groove, of means to feed work through 130

said groove, stitch-forming instrumentalities located beneath the work support, and means to move said instrumentalities bodily and as a unitary structure toward and from the work support in timed relation with the operation thereof.

2. In a sewing machine, the combination with a work support having a work-bending groove, of means to feed work through said groove, stitch-forming instrumentalities comprising a needle and a shuttle, a carrier in which said needle and shuttle are sustained, means to operate the parts, and means to raise and lower the carrier in timed relation to the operation of the needle.

3. In a sewing machine, the combination with a work support having a work-bending groove, of means to feed work through said groove, stitch-forming instrumentalities comprising a needle and a shuttle, a frame on which said needle and shuttle are mounted, means to vibrate the frame toward and from the groove, a driving shaft, and means for operating both the shuttle and the needle from said shaft.

4. In a sewing machine, the combination with a work support having a work-bending groove, of a bender element located in the groove, means for yieldingly holding said element against the work, stitch-forming instrumentalities comprising a needle and a shuttle situated beneath the work support, and means to give said stitch-forming instrumentalities a vibratory movement as a unitary structure relative to the work support.

5. In a sewing machine, the combination with a work support having a work-bending groove, of a bender element yieldingly held against the work and operating to bend the

latter into the groove, means coöperating with the bender element to feed the work through the groove, stitch-forming instrumentalities situated beneath the work support and comprising a needle and a shuttle, a carrier in which said instrumentalities are mounted, means to operate said instrumentalities, and means to vibrate the carrier in timed relation with the movement of said instrumentalities.

6. In a sewing machine, the combination with a work support having a work-bending groove, of means to feed the work through said groove, a pivoted carrier situated beneath the work support, a needle and a shuttle sustained by said carrier, a driving shaft, means operatively connecting said shaft with said needle and shuttle, and means operated by said shaft to raise and lower the carrier.

7. In a sewing machine, the combination with a work support having a work-bending groove, of means to feed the work through said groove, a carrier pivoted to the work support, a needle and a shuttle sustained by said carrier, a driving shaft, means operatively connecting said shaft with said needle and shuttle, a pivotally-mounted elbow lever connected to the frame, and a connection between said lever and shaft whereby the carrier is raised and lowered in timed relation with the operation of the needle.

In testimony whereof, we have signed our names to this specification, in the presence of two subscribing witnesses.

CHARLES F. CLARK.
ALFRED S. CLARK.
